PUMP HEAD FOR VERTICAL DEEP WELL PUMPS

Filed July 10, 1926

FIG. 3

Herbert H. Van Winkle
INVENTOR.

BY *Walter A. Knight*
LAW ATTORNEY

UNITED STATES PATENT OFFICE.

HERBERT H. VAN WINKLE, OF CINCINNATI, OHIO, ASSIGNOR TO THE BONN MACHINE COMPANY, OF CINCINNATI, OHIO, A CORPORATION OF OHIO.

PUMP HEAD FOR VERTICAL DEEP-WELL PUMP.

Application filed July 10, 1926. Serial No. 121,550.

My invention relates to pump heads for vertical deep well pumps and is adapted to operate the piston rod or plunger rod of such a pump. Such pumping apparatus is 5 used principally on oil well pumps but may be used on water well pumps also.

The principal object of my invention is to provide an enclosed self oiling pump head adapted to transform a rotary motion into an 10 oscillating motion whose speed on the down or idle stroke of the plunger rod is greater than the speed on the up or working stroke. Such differential speeds result in increased 15 capacity of the pump to which the head is connected without increasing the piston travel per minute on the up or working stroke, where the power is exerted. This results in an increased number of complete 20 strokes of the piston per minute over mechanisms having equally timed down and up stroke and substantially increases the pumping 25 capacity of the apparatus.

Another object of the invention is to affect such improvement in the details of construction and arrangement of the principal working parts as will permit their being suitably 30 encased, the casing having an oil reservoir adequate for their lubrication and of such shape and size as to contain the gears and bearing portions of all moving parts.

Another object of my invention is to provide means for adapting the mechanism to strokes of different length quickly, readily and without disassembling the power head.

35 In the particular embodiment of my invention selected for illustration:—

Figure 1, is an exterior elevation of the complete power head from the end thru which the walking-beam extends, with the 40 extension arm of the walking beam removed,

Fig. 2, is a horizontal section on the line B—B of Fig. 1, and

Fig. 3, is a vertical section on the line C—C of Fig. 1.

45 Referring now to the drawings, numeral 2 is a cast box-like case carrying bosses 3, 4 extending both inside and outside of the case 2, and 5 extending inside said case. This case 2 is designed having one upper side portion 50 constructed as a removable cover 6 and is held in place in relation to the main body of the case by bolts 7 in suitable flanges 8, 8^a hence by the removal of bolts 7 from flanges 8, 8^a

the upper side portion or cover 6 can be removed giving easy and quick access to all of 55 the working parts contained in case 2.

Case 2 is adapted to receive the gears and other working members of the mechanism. In the boss 3 is journaled a revolving shaft 9 of the inner end of which is securely fastened 60 pinion 10 while on its outer end it carries the pulley 11 or other means of rotatably transmitting power from any suitable source of power. In the boss 4 is journaled a revolving shaft 12 on the inner end of which is securely 65 fastened gear 13 while on its outer end it is supplied with the nut 14 and loose collar 15 for holding shaft 12 and gear 13 in position.

Gear 13 meshes with pinion 10 and also carries crank pin 16 which is provided with removal journal boxes 18, 18 fitted so as to operate freely in the slot 17^a of the walking beam 17.

The walking beam 17 is pivoted on the inner end of the stud 19 which is securely fastened 75 in boss 5 forming a part of case 2. The walking beam 17 on its outer end is provided with a flange 25 to which is bolted with short bolts and nuts 20 an extension arm 21, having flange 26 and so designed as to be readily connected 80 by links 22 or other suitable means to the deep well piston or plunger rod 23.

The free end of the walking beam 17 extends outside case 2 through the slot 24, and it will be readily understood that by having 85 different lengths of extension arms 21 different lengths of stroke or movement can be provided to suit the stroke of the deep well pump rod 23 to which it is desired to connect my vertical deep well power head without opening 90 the case 2 or adjusting any parts therein.

It will be apparent that by the rotation of pinion 10, thru pulley 11 and shaft 9, the gear 13 will be rotated and its crank pin 16, whose journal boxes 18, 18 work freely in the slot 95 17^a of the walking beam 17 will cause an oscillating movement of the walking beam 17 on its pivot 19 suitable for connection to deep well piston or plunger rod 23 which is the object of the apparatus.

100 The case 2 is so formed that a suitable amount of lubricating oil O can be placed therein so the lower rim of gear 13 will be submerged, which in its revolutions carries the lubricant to pinion 10 and shafts 9 and 12 105 also on each downward motion of the walking

beam 17 it will dip into the lubricant thus lubricating pin 16 and boxes 18, 18 together with shaft pin 19.

I do not intend to limit myself to the precise form shown, but claim as within the scope of my invention all forms of power heads readable on the claims.

I claim as my invention and desire to secure by Letters Patent of the United States:—

10 1. A walking beam slotted at its inner end and pivoted outwardly of said slot, said walking beam terminating in a flange at its outer end, flanged lengthening attachments and means for securing said walking beam and one of its lengthening attachments together.

15 2. A walking beam slotted at its inner end

and pivoted outwardly of said slot and interchangeable means of different lengths attachable to the outer end of said walking beam for varying its length.

20 3. In combination with a pump jack, a walking beam slotted at one of its ends and pivoted near said slot, the other end terminating in a stub, interchangeable extensions of said walking beam of different lengths adapted to be secured to said stub and means for securing any one of said extensions to said stub.

25 In testimony whereof I have hereunto set my hand.

HERBERT H. VAN WINKLE.
